CLAIM

I claim the ornamental design for a telephone, as shown and described.

DESCRIPTION

FIG. 1 is a front perspective view of a telephone of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof;

FIG. 8 is a front perspective view thereof shown with a handset; and,

FIG. 9 is a front perspective view thereof shown with a handset and in an alternate down position.

The broken line showing of the telephone leg feature, handset, coiled cord, and other environmental structures is for illustrative purposes only and forms no part of the claimed design. The unshaded region on the right side of the telephone (shown in FIGS. 1, 5, 8, and 9), the unshaded region on the left side of the telephone (shown in FIG. 4) and the unshaded region on the rear of the telephone (shown in FIGS. 3 and 7) that are defined in part by broken lines, and in part by solid lines, are not part of the claimed design. The broken lines and unshaded regions form no part of the claimed design.
